UNITED STATES PATENT OFFICE.

KARL MAIER, OF STUTTGART, GERMANY, ASSIGNOR TO THE FIRM OF UNION SPECIAL-MASCHINENFABRIK G. M. B. H., OF STUTTGART, GERMANY.

CHANGE-MAKING MACHINE.

1,115,849.

Specification of Letters Patent.

Patented Nov. 3, 1914.

Application filed March 1, 1910. Serial No. 546,650.

To all whom it may concern:

Be it known that I, KARL MAIER, a citizen of the German Empire, residing at Stuttgart, in the Kingdom of Wurttemberg, Empire of Germany, have invented certain new and useful Improvements in Change-Making Machines; and I do hereby declare the following to be a full, clear, and exact description of the invention, such as will enable others skilled in the art to which it applies to make and use the same.

This invention relates to a combined registering and change giving machine, such as is more particularly employed in shops and the like.

The improved machine belongs to the type in which cash received and sales keys are provided, and in which in addition to the automatic registering of the various amounts, the difference is mechanically issued, so that the salesman himself has nothing to do with the money. Such machines have not yet come into practical use, as the constructions designed therefor are much too complicated to be adopted, and consequently in the long run do not work with certainty, as, on account of the numerous moving parts employed, they easily get out of order, more particularly when largely used. Now by this improved machine these disadvantages are entirely avoided, and it is particularly characterized by its very simple construction.

The invention will now be more particularly described in connection with the accompanying drawings, which give examples of some forms of construction.

Figure 1 is a front view in perspective of the machine as a whole; Fig. 2, a plan view of a portion of the recording band; Fig. 3, a sectional side view of the machine; and Fig. 4, a diagram explaining the action of the working parts; Fig. 5 is a plan view of the working parts; Fig. 6, a front view of one half of them; Fig. 7, a side view on an enlarged scale of Fig. 6; Fig. 8, a side view of another form of construction.

The registering and change giving machine 1 in accordance with this invention, is provided in the ordinary way with a series of keys 2 for the dollars received, and a similar series of keys 3 for the cents received, a series of keys 4 is also provided for the amounts of the sales in dollars, and

a similar series 5 for the amount of the sales in cents.

The ejection, that is to say the delivery of change is effected by means of an ejector 6, which encounters the uppermost coins 7 which are piled up, sorted in a coin frame 8, 60 and are constantly drawn upward by a spring. The ejected coins 7 then fall into a single common hopper or funnel 9, beneath the outlet of which a scoop 10 may be held (Figs. 1 and 3). Now in order to 65 register the payments, the sales and the change given, an indicating device 11 of known construction is provided which prints the amounts automatically side by side in a visible manner on a strip 12 by means of 70 a printing device 16. At the same time the sums received can then be seen and the amounts checked through a window 13 and the amounts of the sales through a window 14, and the change given through a window 75 15 (Fig. 1).

The keys, as is usual with coin issuing apparatus, are provided at their lower ends with bars 17, the number of teeth and arrangement of which corresponds with the 80 value of the key in question. These bars 17 encounter levers 18 and cause these to turn in one direction. According to this invention the levers for the dollars are formed as double-armed levers, by means of which 85 they may be turned in two directions, the keys 2 encountering the part 18 of the levers and the keys 4 the part 19. The cents levers are only single and are moved in the same direction by the cash received keys and also 90 by the sales keys. Of course the dollars arrangement might be employed for the cents and vice versa, the cents arrangement for the dollars, but it is not preferable to do so because it is rarely in the case of the dollars 95 that amounts of one hundred have to be calculated, while with cents this is mostly the case.

Each of the levers 18, 19 and 20 is connected by a link 21 with a bell crank lever 100 23, one such bell crank lever and one such connecting mechanism being provided for each of the ejectors 6. All these bell crank levers 23 turn loosely on a shaft 24 common to all, and have a slot 25 in which a guide 105 pin 22 provided, for instance, with a roller, engages, which pin is carried by the link 21 (Figs. 3 and 7). In a normal position the

pins 22 of the dollars side are all uncoupled or out of action of the spindle 37 and lie at the outer end, that is to say at the front end of the elbow levers 23. Now if one of the 5 keys 2 be depressed, the pin 22 moved by it is thereby displaced in the slot 25 into the other end position and coupled with the ejecting spindle 37. In order to automatically retain the pin 22 in each of the end 10 positions, a lever 26 is provided which is loosely pivoted on the spindle 24 and which is under the action of a spring 27 and is provided with notches 28, in which the pin 22 rests, these notches 22 being of such a 15 form, that a slight pressure suffices to transfer the pin 22 from one end position to another. On the cents side on the contrary, the pins 22 lie in their normal position at the inner end of the slots 25 and are coupled 20 with the ejecting spindle 37. When the sums received and sales keys are depressed, so many of these pins are uncoupled that only the excess amount received remains adjusted and capable of being ejected.

25 The bell crank levers 23 are connected by levers 29 and 30 with the ejectors 6, so that when the elbow levers turn the ejectors throw the uppermost coin into the hopper 9, that is to say they are set in operation. 30 The elbow levers 23 are turned by means of a spindle 37 with projections 38 and in the form of construction shown this turning movement is produced by means of a hand lever 31, but suitable projections 43 35 might equally well be provided on the bars 17 of the sales keys, which would effect this operation (Fig. 8). In this case the ejecting levers preferably turn directly on the shaft 24.

40 The hand lever 31 and the lever 33 are mounted on one shaft 32 and move, by means of a link 34, a pin 35, which is moved in a guide 36, which pin in turn depresses a continuous shaft 37 when the hand lever 31 45 is put over, that is to say moved against the pin 22. Now this shaft 37 has a stop or contact 38 (Fig. 6) for each of the pins 22, which stop encounters its pin 22 when the latter is in the coupling or engaged position 50 and thereby the respective amount is ejected. At the same time the indicating mechanism 11 is operated by the hand lever 31 by means of an arm 39 mounted on the shaft 32.

55 Now in order for the machine to work correctly, the dollars keys, when the sale price only amounts to whole dollars, must merely be coupled with those ejectors the values of which make up the total amount less one dollar, which must be reissued.

60 This missing dollar is then adjusted from the cents sale keys 5. For the case when the amount of the sale contains no cents, a 00 sale key 40 is provided, which key on the one hand throws out of action all cents 65 couplings, and on the other hand encounters

a continuous yoke 41, which then couples with an elector 42 on the dollars side, in order to adjust the arrangement for the missing dollar so that the latter can be ejected. The 00 key 40 in the penny device 70 is actuated when only single dollars are calculated. This key 40 actuates the rocking arm 41 (Fig. 5) and the latter engages the "one dollar" ejector.

The action of the improved machine is as 75 follows:—Say an amount of \$20 has been received, while the sale price is only \$17.60, and thus the purchaser must receive \$2.40 change, the salesman then first depresses the \$20 received key 2, whereby the yokes 80 18 and 19 by means of the transfer member hereinbefore explained, set ready for operation all the ejectors 6 on the dollars side, necessary for this amount, that is to say throws into action their pins 22. The dollar sales keys 4 belonging to \$17 are then 85 depressed and thus in consequence of the tooth arrangement on their bars 17 again push back all the pins 22 on the dollars side, the ejectors 6 of which are not to operate. Thus in this case there only remain the 90 ejectors for two dollars in the position ready for ejecting. In the same manner the cents sales key 5 is depressed, which throws out of action the ejector making up the amount of 60 cents, that is to say the completion up to 100, so that only 40 cents are given in change. The hand lever 31 is now put over and accordingly \$2.40 drop into the hopper 9. Should the amount of the sale only 95 amount to dollars, for instance \$16, while \$20 is paid in, the dollar keys, as before mentioned, must be depressed, and also the cipher cents sales key 40, as there are no cents in the sale price. This key 40 then 100 adds the missing dollar to the 8 dollars adjusted by the dollar keys, so that four dollars are adjusted and may be ejected. Finally if the amount of the sale only 105 amounts to cents, for instance 76 cents and 110 80 cents are paid, the depressed 80 cents receipts key and the 76 cents sales key throw out of action all the ejectors which could eject more than four cents.

The parts 18—22 after each giving of 115 change return compulsorily to their initial position. If, for instance, they assume the position shown in Fig. 8 on the depression of the amount received keys 2 and 3, which act on the yokes 18, they are retained in this 120 position by the notches 28 of the lever 26 until on the return of the hand lever 31 a bar descends on all the sales cranks and releases all the couplings which are still connected.

I declare that what I claim is:

1. In a change-making machine, the combination with two sets of keys for receipts and sales respectively, ejectors, levers adapted to be directly acted upon by the keys, 130

coupling members between the levers and the ejectors, including bell crank levers and pin and link connections and brought into and out of effective operative position by 5 the keys, a common driving device directly connected with the coupling members, whereby the operation of the receipts and sales keys in operating upon the levers effect the coupling or releasing of the ejectors 10 with the common driving device of the coupling members.

2. In a change-making machine, the combination with two sets of keys for receipts and sales respectively, ejectors, double- 15 armed levers adapted to be directly acted upon by the keys, coupling members between said double-armed levers and the ejectors, including bell crank levers and pin and link connections, and brought into and 20 out of effective operative position, by the keys, a common driving device directly connected with the coupling members, whereby the operation of the receipts and sales keys in operating upon the double-armed levers 25 effect the coupling or releasing of the ejectors with the common driving device of the coupling members.

3. In an indicating and change-giving machine having receipt and sales keys, ejectors for the coins, means operated by the sales and receipt keys for throwing out of 30 operating position all the ejectors except those representing the amount received and

the amount of sales, and means for operating the ejectors not rendered inoperative, 35 said means including bell crank levers.

4. In a registering and change-giving machine, receipt and sales keys, double armed levers, the arms of which are respectively acted upon by the keys, ejectors, 40 bell crank lever connected with each ejector, and a pin and link connection between the bell crank levers and the double armed levers.

5. In a registering and change-giving 45 machine, receipt and sales keys, double armed levers, the arms of which are respectively acted upon by the keys, ejectors, a bell crank lever connected with each ejector, and a displaceably connected pin and link 50 connection between the bell crank lever and the double armed levers.

6. A registering and change-giving machine, means for giving change including 55 ejectors, bell crank levers for operating them, a common bar having a catch or stop 38 for each ejector, a catch pin 22 operated upon by the stop, and connections between the catch pin and the ejector for turning the bell crank lever for operating the ejector. 60

In testimony whereof I affix my signature, in presence of two witnesses.
